UNITED STATES PATENT OFFICE.

JOHN N. WHITEHOUSE, OF NEWARK, NEW JERSEY.

DESIGN FOR A BABY-RATTLE OR TOY.

47,126.

Specification for Design.

Patented Mar. 16, 1915.

Application filed December 24, 1914. Serial No. 878,831. Term of patent 3½ years.

To all whom it may concern:

Be it known that I, JOHN N. WHITEHOUSE, a citizen of the United States, residing at Newark, in the county of Essex and State of New Jersey, have invented a new, original, and ornamental Design for Baby-Rattles or Toys, of which the following is a specification, reference being had to the accompanying drawing, forming part thereof.

In the drawing: Figure 1 is a plan view of a baby rattle or toy showing my invention; tion; Fig. 2 is a side elevation of the same, and Fig. 3 is a plan view showing the opposite face of the article from that shown in Fig. 1.

I claim:

The ornamental design for a baby rattle or toy, as shown.

JOHN N. WHITEHOUSE.

Witnesses:

MARY H. LEWIS,
HELEN V. FITZPATRICK.
